UNITED STATES PATENT OFFICE

CHARLES THOMAS SMITH, OF UTICA, NEW YORK.

IMPROVEMENT IN BOBBINS FOR SPINNING-MACHINES.

Specification forming part of Letters Patent No. 58,903, dated October 16, 1863.

To all whom it may concern:

Be it known that I, CHARLES THOMAS SMITH, of Utica, in the county of Oneida and State of New York, have invented a new and useful Improvement in Wood Bobbins, now in use in woollen-mills; and I do hereby declare that the following is a full, clear, and exact description of said invention, reference being had to the annexed drawings, with letters of reference marked thereon, being a part of this specification.

The nature of my invention or improvement in bobbins consists in making the bands or tubes of sheet-zinc.

The bobbins, after they are wound, have to go through a steaming process, which has the effect to prevent the yarn from kinking at each side of the piece of cloth while the weaving is going on. During this process these zinc tubes, or barrels are found to be superior to all others, as they do not rust or corrode, as would be the case if made of sheet-iron; and they will not shrink or swell or grow rough, as is the case in wooden bobbins, which swell in the steaming process, and sometimes before used they shrink to such a degree that whole cops often slip off while weaving, causing great waste and loss. The bobbins made of zinc are consequently smooth, and the yarn all runs off without waste or loss.

Another advantage these possess over wooden bobbins is this: They are smaller and stronger and grow smooth by use; and as all

bobbins for weaving have to be wound the same size, they are found to hold one-third more yarn; and they are as lasting as the machinery itself, and not liable to get out of order.

To enable others skilled in the art to make and use my invention, I will describe their construction and operation.

First. The barrels or tubes are made of sheet-zinc. The ends of the tubes A, B, and C, or 1, 2, and 3, are filled with fused metal at D, Section No. 3, to make them strong, with a taper hole in the end to admit of a taper spindle, as seen in Section No. 3 at D.

Second. Section No. 3, at E, shows the manner of securing the tubes or barrels to the wooden flanges F, which is done by pins or by indentations in the metal on the inside of the tube into the wooden end or flanges, or by dividing or splitting the end of the tube into four sections, and turning them over the end onto the flanges, which fasten them securely.

What I claim as my invention, and wish to secure by Letters Patent, is—

A filling-bobbin the tube or barrel of which is formed or manufactured of sheet-zinc, with a wooden head or flange, as above described, the bore of the barrel at its tip being made tapering, in the manner and for the purpose as herein set forth.

CHARLES THOMAS SMITH.
